UNITED STATES PATENT OFFICE.

GEORGE ARCHAMBEAULT, OF WATERBURY, CONNECTICUT.

WINDOW SHADE AND CURTAIN BRACKET.

No. 800,423.

Specification of Letters Patent.

Patented Sept. 26, 1905.

Application filed April 10, 1905. Serial No. 264,853.

To all whom it may concern:

Be it known that I, GEORGE ARCHAMBEAULT, a citizen of the United States, and a resident of Waterbury, in the county of New Haven 5 and State of Connecticut, have invented certain new and useful Improvements in Window Shade and Curtain Brackets, of which the following is a specification.

This invention relates to new and useful improvements in window curtain and shade brackets, and especially refers to a detachable shade-bracket which can be applied to the casing without defacing or injuring the same.

It is the object of my invention to produce a bracket which will not only suffice to accommodate a curtain-pole, but also a pair of shade-rolls and a rod for sash-curtains as well; further, to produce this bracket in an inexpensive way, which will permit of it being manufactured and sold cheap and within the reach of the class of people who would require a device of this kind—namely, those who are living in rented houses and have occasion to remove the brackets when moving.

With the above and other minor objects in view my invention resides and consists in the novel construction and combination of parts shown upon the accompanying sheet of drawings, forming a part of this specification, upon which similar characters of reference denote like or corresponding parts throughout the several figures, and of which—

Figure 1 shows a front elevation of my improved bracket complete as applied in use and supporting therein the ends of a curtain-pole and shade-rollers, which are represented as being broken off. Fig. 2 is a side elevation of the bracket shown in Fig. 1, the pole and rollers being omitted. Fig. 3 is a slightly-enlarged perspective view of the bracket shown in Figs. 1 and 2, but having the sash-curtain extension omitted.

Referring in detail to the characters of reference marked upon the drawings, A indicates the upper portion of the bracket, which is formed of sheet metal containing an extension B, with a pocket C for the reception of one end of a curtain-pole, as indicated by U. Extensions E and F are also provided for the support of the end of shade-rollers V and W, which may be of any preferred construction. One of these extensions is shown as being longer than the other to insure a free operation of either curtain irrespective of the other, 55 and which construction permits of the use of two curtains upon a window, if desired—as,

for instance, in a sick-room, where a temporary dark shade might be desirable in addition to the regular light shade, which might be permanently installed. The metal of the upper end of the bracket is twisted, as at G, and contains two inward extensions having deflected engaging ends H, as indicated, for the engagement of the top edge of the window-casing. The lower portion of the bracket is also twisted, as at I, having a divided end J, over which a slideable clamp K is mounted for the engagement of the under edge of the window-casing. Intermediate of the divided end J, I provide a clamping-lever L, which is pivoted to a stud O and is provided with cam-faces M and N at either end, one of said ends being longer than the other and each adapted to engage the under side of the clamp K in a way to tightly force the same up against the casing for the proper securement of the bracket. The difference in the length of this lever from its pivot to its ends is designed to provide for different widths of casings, as will be obviously apparent. The said lever turns upon the pivot and would be operated so that its cam-face would first engage the under side of the clamp and gradually force the same up into position until the right-angle shoulder P of the lever registers with the under face of the clamp in a way to retain and support the same. In instances where sash-curtains would be required the same could be attached to the extension Q of this bracket, which extension is shown as formed of wire and attached to the pivotal screw O. It may obviously be formed of any desired length, and its lower portion R is preferably turned at a right angle, with its end S pointed and deflected inward to engage a crack in the face of the casing in a way to not deface the same. Upon this horizontal portion R is a holder T, which I have preferably shown in the form of a pin to receive the end of a sash-rod, as indicated in dotted lines. In practice two of these brackets would be required to support a pole and shades. One bracket to be arranged on either side of the top of the casing.

Having thus described my invention, what I claim, and desire to secure by Letters Patent, is—

1. A window curtain and shade bracket, comprising a sheet-metal body portion having arms for the support of a curtain-pole, and shade-rollers, an extension to engage the top of a window-casing, and a divided lower end,

a slidable clamping-piece mounted upon said lower extension and a clamping-lever pivoted between said divided end having two cam-face-engaging ends each at a different distance 5 from the pivotal center of the lever.

2. A device of the kind described, the same comprising a sheet-metal bracket having supports for a curtain-pole and shade-rollers, the upper portion of the bracket being twisted 10 turned in down and pointed to engage the top of the casing, the lower portion of the bracket also being twisted and divided, a slidable clamp mounted upon said lower portion adapted to engage the under side of the casing, a 15 lever pivoted intermediate of said divided portion having opposite cam-faces to engage the under side of the clamp.

3. A window curtain and shade bracket, comprising a sheet-metal body portion having 20 arms for the support of a curtain-pole and a shade-roller, an extension to engage the top of the window-casing, a divided lower end, a slidable clamping-piece mounted upon said lower end, and a clamping-lever pivoted in 25 said divided end having two cam-face-engaging ends each at a different distance from the

pivotal center of the lever, and an extension attached to the divided end and containing a support thereon for the sash-curtain rod.

4. A window curtain and shade bracket, 30 comprising a sheet-metal body portion having arms for the support of a curtain-pole and shade-rollers, an extension to engage the top of the window-casing, a divided lower end, a slidable clamping-piece mounted upon said divided lower end, a clamping-lever pivoted in 35 said divided end having two cam-face-engaging ends each at a different distance from the pivotal center of the lever, a pivotal screw upon which the lever is mounted, a depending extension attached to said pivotal screw having its lower portion deflected crosswise and its end pointed, and disposed inward, and a sash-curtain-rod support mounted thereon.

Signed at Bridgeport, in the county of New 45 Haven and State of Connecticut, this 3d day of March, A. D. 1905.

GEORGE ARCHAMBEAULT.
